UNITED STATES PATENT OFFICE.

GUILFORD C. ATWOOD, OF AUSTIN, COLORADO.

BROODER AND HEATER.

1,411,075.

Specification of Letters Patent. Patented Mar. 28, 1922.

Application filed June 18, 1921. Serial No. 478,599.

To all whom it may concern:

Be it known that I, GUILFORD C. ATWOOD, a citizen of the United States, residing at Austin, in the county of Delta, State of Colorado, have invented certain new and useful Improvements in Brooders and Heaters; and I do hereby declare the following to be a full, clear, and exact description of the invention, such as will enable others skilled in the art to which it appertains to make and use the same.

This invention relates to new and useful improvements in brooders and particularly to brooders which do not use lamps, or similar sources of heat.

One object of the invention is to provide a brooder which is simple and cheap in construction, durable and efficient in operation, and one wherein little attention is needed.

Another object is to provide a device of this character which may be easily and quickly taken apart so that the same may be thoroughly cleansed.

Other objects and advantages will be apparent from the following description when taken in connection with the accompanying drawing.

In the drawing:

Figure 1 is a front elevation of the brooder.

Figure 2 is a vertical longitudinal central sectional view through the brooder.

Figure 3 is a vertical transverse central sectional view through the brooder.

Referring particularly to the accompanying drawing, 10 represents a rectangular structure projecting inwardly from the side walls of which are the lugs 11, and in one end of which is formed an opening 12 for

the passage of the chicks, said opening being controlled by the hinged door 13. Disposed within the lower portion of the structure 10, and forming the floor of the brooder, is the bottom wall 14. Seated within the upper

portion of the structure 10, and resting on the lugs 11, is the top wall 15, of the hover, fabric curtains 16 being secured to and depending from the said wall. In the center of the wall 15 is formed a comparatively large

circular opening 16', the purpose of which will presently appear herein. Disposed on the upper portion of the structure 10, and having a depending peripheral flange 17, embracing the outer portions of the walls of the structure, is the removable cover of the

brooder 18. In the center of the cover 18 there is formed an opening 19, and hinged to the upper face of the cover, and arranged to lie over the said opening, is a closure door or cover cap 20, said closure having depending peripheral flanges 21, whereby the top wall of the closure is properly elevated above the cover 18.

Disposed on the bottom wall 14 is a jug of stone, or other suitable receptacle 22, the upper portion of which extends upwardly through the openings 16 and 19, and into the cap 20, said jug being filled with hot water. Covering the upper portion of the jug, and extending downwardly to a point a predetermined distance above the bottom of the jug, is an asbestos casing 23 which serves to retain the heat of the water within the jug. Resting on the floor 14, and surrounding the lower exposed portion of the jug, and a portion of the lower end of the asbestos casing, is a wire screen cylinder 24, which prevents the chicks from coming in direct contact with the hot jug, and especially the exposed portion. The jug and its asbestos casing are inserted and removed through the openings in the top of the brood chamber and the cover, when the cap 20 is swung into open position.

Openings 10' are formed in the walls of the structure 10 to provide for proper ventilation of the interior of the brooder.

What is claimed is:

A brooder including a rectangular structure having a removable bottom, a brood hover in the structure comprising a centrally apertured cover having depending fabric curtains, a removable flanged cover for the structure having a central opening, a flanged cap hinged to the cover and closing the opening thereof, a hot water receptacle on the bottom and extending through said openings and into the said cap, a protective and heat retaining casing on the water receptacle extending to a point adjacent the bottom of the receptacle, and a guard screen cylinder surrounding the lower exposed portion of the receptacle and part of the enclosed portion thereof.

In testimony whereof, I affix my signature, in the presence of two witnesses.

GUILFORD C. ATWOOD.

Witnesses:

H. W. BULL,
IRMA WESTEN.
